UNITED STATES PATENT OFFICE

HANS GLEICHMANN, OF FALKENHAIN, NEAR SPANDAU, AND WILHELM GUMZ, OF BERLIN-CHARLOTTENBURG, GERMANY, ASSIGNEES TO SIEMENS-SCHUCKERTWERKE, GESELLSCHAFT MIT BESCHRANKTER HAFTUNG, IN LIQUIDATION, OF BERLIN-SIEMENSSTADT, GERMANY, A CORPORATION OF GERMANY

AUTOMATIC STOKER FOR CIRCULAR GRATES

Original application filed October 7, 1926, Serial No. 140,188. Divided and this application filed September 20, 1929, Serial No. 393,968, and in Germany May 3, 1926.

Our invention relates to automatic stokers for circular grates as are employed for cylindrical vertical combustion chambers for boilers or the like, and as are illustrated in our copending application for steam generators, Serial No. 140,188, filed October 7, 1926, of which the present application is a division. The specific features covered in the present application refer to the type of stoker illustrated in original Figs. 6 and 7 of the aforementioned parent application.

It is known in the prior art to supply solid or lump fuel to grates by means of reciprocating pistons which operate at the bottom of a fuel supply chute in such manner that at each stroke of the piston or pistons the fuel which has run to the bottom of the chute is pushed forward onto the grate. The present invention in particular relates to the application of this idea in an improved form to circular grates in which the fuel is supplied by a number of pistons from the grate periphery towards the center, in such manner that each piston pushes the fuel which is supplied to it into an individual retort which is open at the top and in which the fuel slides on the grate towards the center. By this arrangement the uniform travel of the fuel during combustion is insured.

30 Our invention is illustrated in the accompanying drawings in which

Fig. 1 represents in longitudinal vertical section one half of the grate and the operating mechanism,

35 Fig. 2 represents a plan view thereof, partly diagrammatic the combustion chamber wall being shown in horizontal section on the line 2—2 Fig. 1, and

Fig. 3 represents an enlarged fragmentary 40 detail of the gear drive 10, 10^a for the cam carriage 22, in plan view as shown in Fig. 2.

Referring to the drawings 1 represents the lower portion of the combustion chamber at the bottom of which a circular grate 2 is arranged which consists of a plurality of radially extending ridges 2^a which extend from the periphery to within a suitable distance from the grate center. Between these ridges are thus formed open retorts 3 into which the 50 fuel is pushed by means of pistons 5, one

piston being arranged in radial alignment with each retort as shown in the drawings. Above each piston a supply chute 4 is arranged through which the fuel is supplied in front of the piston when the latter is withdrawn, and in the position shown in Fig. 1 in full lines. When the piston is moved to the left as shown in Fig. 1 into the dotted position by mechanism to be described presently, the fuel is pushed into retort 3 between the ridges 2^a in which it is forced during the succeeding piston strokes gradually towards the grate center while it is consumed, so that the ash from all retorts drops into the ash pit 15. At the bottom of this ash pit is arranged a conical grinder 16 operated by a motor 18 by which the ash is granulated, whereafter it is delivered onto discharge chute 17.

The combustion air required from below the fuel bed is supplied through a circular main air duct 19 from which the air passes through individual discharge openings 19^a into an air chamber 14 arranged underneath the grate bottom 13. The ridges 2^a are provided with suitably shaped openings 21 on their sides which form the retorts, so that the air from chamber 14 can pass into the interior of these ridges and out through the openings 21 into the fuel.

The individual pistons for the retorts are 80 operated in the following manner.

Outside of pistons 5 is provided a rotatable ring 22 which travels on rollers 11 as shown in Fig. 1 and which is laterally guided by guide rollers 12. The outer periphery of this ring is provided with teeth which mesh with a driving pinion 10^a driven by means of the worm gear 10 through a motor 9, as shown in detail in Fig. 3. On ring 22 is provided a sinusoidally shaped cam rail 8 whose form is indicated in Fig. 2 partly in full lines and partly in dash and dot lines. Each piston is provided with a piston rod 23 which extends radially across cam rail 8, and is provided with two vertical guide rollers 20 which are disposed on each side of cam track 8. Each piston rod 23 is supported at its outer end in a slide bearing 7. It will thus be understood that when the cam rail 8 is rotated around the grate by motor 9, each piston

will be reciprocated in radial direction. The pitch of cam rail 8 is chosen so that when for instance in Fig. 2 piston rod I has withdrawn its piston 5 into its outermost position, 5 the next adjacent piston rod II has thrust its piston into the innermost position. Thus, speaking of the entire circular group of pistons arranged around the grate, adjacent pistons alternately move inward and outward 10 so that the fuel supply onto the grate as a whole is practically uniform and continuous. By suitably controlling the speed of rotation of cam 8 it is very easy to exactly regulate the fuel supply per unit of time.

15. We claim:

1. An automatic stoker device for furnaces or the like, comprising a circular grate divided radially into a plurality of retorts, means for feeding fuel to said retorts including a radially disposed piston for each retort adapted to push the fuel, supplied, in the direction of the grate center, a circular cam rail rotatably disposed around said grate, and suitable connection between said cam rail and said pistons to reciprocate the latter when said cam rail is rotated around said grate.

2. An automatic stoker device for furnaces or the like, comprising a circular grate divided radially into a plurality of retorts, means for feeding fuel to said retorts including a radially disposed piston for each retort adapted to push the fuel, supplied, in the direction of the grate center, an annular cam carriage rotatably disposed around said grate, a sinusoidally curved cam rail mounted on said carriage and cam rollers connected to each of said pistons and engaging both sides of said rail and adapted to reciprocate said pistons when said carriage is rotated, vertical guide rollers disposed along the side of said carriage for rotatably guiding it, and means for rotating said carriage.

3. An automatic stoker device for furnaces or the like, comprising a circular grate and a plurality of radially movable pistons disposed around the grate periphery and adapted to feed fuel onto said grate, an annular cam carriage disposed to rotate around said grate and having a sinusoidally curved cam rail mounted upon said carriage and cam rollers connected to each of said pistons and engaging both sides of said rail and adapted to reciprocate said pistons when said carriage is rotated, vertical guide rollers disposed along the side of said carriage, for rotatably guiding it, and means for rotating said carriage.

4. An automatic stoker device for furnaces or the like, comprising a circular grate divided radially into a plurality of retorts, means for feeding fuel to said retorts including a radially disposed piston for each retort adapted to push the fuel, supplied, in the direction of the grate center, and a com-

mon operating device adapted to simultaneously reciprocate said pistons.

5. An automatic stoker device for furnaces or the like, comprising a circular grate divided radially into a plurality of retorts, means for feeding fuel to said retorts including a radially disposed piston for each retort adapted to push the fuel, supplied, in the direction of the grate center, and a common operating device for all of said pistons, adapted to simultaneously reciprocate adjacent pistons in opposite directions, whereby a substantially continuous and uniform supply of fuel from the grate periphery toward the grate center is attained.
